FIG. 4.

UNITED STATES PATENT OFFICE.

ALBERT J. GRANBERG, OF SAN FRANCISCO, CALIFORNIA.

COUNTING ATTACHMENT FOR FAUCETS.

1,243,400.

Specification of Letters Patent. Patented Oct. 16, 1917.

Application filed January 26, 1917. Serial No. 144,655.

To all whom it may concern:

Be it known that I, ALBERT J. GRANBERG, a citizen of the United States, residing at San Francisco, in the county of San Francisco and State of California, have invented new and useful Improvements in Counting Attachments for Faucets, of which the following is a specification.

The object of the present invention is to provide means whereby the quantity of liquid, such as gasolene, which is supplied from a faucet, can be automatically registered.

At present it is the common practice at gasolene supply stations, at which gasolene is supplied by the bucket, each bucket containing say five gallons, for the salesman to measure the quantity of gasolene which has been supplied from the faucet by counting the number of buckets. It often happens that the salesman loses count of said number, and counts it incorrectly, and thus charges the customer with more or less gasolene than he has obtained.

It has been attempted to overcome this difficulty by providing a counting device operated by the handle which controls the faucet valve, but this arrangement is not satisfactory, for the reason that, in order to supply the exact quantity of gasolene desired, the salesman often has to move the handle several times to and fro a short distance before finally shutting off the gasolene.

My present invention has for its object to provide a measuring device by which the registering of the quantity of gasolene supplied will be effected automatically, and with which the gasolene can be supplied equally as readily as before.

In the accompanying drawing, Figure 1 is a broken side view of a faucet for dispensing gasolene or other liquid and equipped with my invention; Fig. 2 is a plan view thereof; Fig. 3 is a section on the line 3—3 of Fig. 2; Fig. 4 is a view of the end of the faucet.

Referring to the drawing, 1 indicates a faucet having a valve 2 controlled by a handle 3. Formed integral with, and extending from, the spout of the faucet is a casing 4, between the walls of which is pivoted, as shown at 5, a lever 6. The upper surface of said casing is concave, to receive the handle of a bucket hanging from the faucet, and in such a position that the gasolene will be discharged from the spout approximately into the center of said bucket.

The upper edge of said lever 6 can extend through a slot 7 in the top of the casing 4 and is normally raised into such position by means of a spring 8, coiled around a pin 9, 60 depending from said lever, and also around a pin 10, extending upwardly from, and screwed into, a lug 11 of the faucet body, said pin 9 being adapted to abut against the pin 10 when the lever is depressed, in which 65 position the upper edge of the lever is on the same level as the upper surface of the casing 4. To the free end of said lever is secured a spring pawl 13, adapted to engage any one 70 of a series of ten teeth of a ratchet wheel 14 actuating a counting device 17 supported by a bracket 16 within the casing 4, the numerals of the counting device appearing in succession through an opening 15 in an end wall 20 of the casing 4. A spring-actuated dog 18 engages the teeth of the wheel 14 and prevents them returning with the pawl.

In order to bring all the wheels of the counting device to zero, there is provided a 80 gear wheel 22, extending below the casing 4, so as to be capable of being turned by a finger, and which meshes with a gear wheel 27, which meshes with a pinion 26, secured to, and rotating with, the wheel 14. 85

Also extending from the first spring pawl is a second spring pawl 19 which similarly engages the teeth of a ratchet wheel 25 actuating a second counting device 21 supported by said bracket 16, said second series 90 being used to register the number of buckets filled from the faucet during the whole, or a long period of, time while the first series is used to register the number of buckets supplied each customer.

The spring 8 is of such strength that the lever 6 is not depressed to the same level as the upper surface of the casing until the bucket has been more than half filled with gasolene, so that the device does not register 100 if only a small amount of gasolene is allowed to flow into the bucket.

In order to prevent the counters being operated unless the faucet is open, the faucet valve is formed on one side with a horizontal groove or recessed portion 29, which, when the valve is closed, can receive a rear head 30 on a slide-piece 31, slideable through a bearing 32 and drawn toward said groove 29 by a spring 34 attached thereto and to 110 the bearing 32, said slide-piece 31 being pivotally connected, as shown at 34, with an

- arm 36 pivoted on the faucet body, as shown in 37, which, when in its rear position, can engage a depending portion 38 of the lever 6 and prevent it from being depressed.
- 5 When the valve is opened, said groove is out of the path of said slide-piece 31, so that the head 30 is moved toward the bearing 32 against the force of the spring 34 and the arm 36 is moved out of the way of the portion 38 of the lever 4 and the lever 6 is not prevented from being depressed. Consequently, counting of the buckets can take place only when the valve is open.

I claim:—

- 15 1. In combination with a downwardly discharging faucet body having a counting and registering casing above the same, counting and registering mechanism in the forward portion of said casing, a lever pivoted above the faucet body in the rear end of the counting and registering casing, said counting and registering casing having an opening immediately above the discharge opening of the faucet, and said lever extending above the edges of said opening and adapted to be depressed to the level of said edges by the weight of a vessel of which the bail is deposited upon the portion of the lever extending above said edges, a spring for raising said lever when the bail is removed, and means carried by the front end of said lever for actuating the counting and registering mechanism by the vertical reciprocatory movement of the lever.
- 20 2. In combination with a downwardly discharging faucet body having a counting and registering casing above the same, counting and registering mechanism in the forward portion of said casing, a lever pivoted above the faucet body in the rear end of the counting and registering casing, said counting and registering casing having an opening immediately above the discharge opening of the faucet, and said lever extending above the edges of said opening and adapted to be depressed to the level of said edges by the weight of a vessel of which the bail is deposited upon the portion of the lever extending above said edges, a spring for raising said lever when the bail is removed, and means carried by the front end of said lever for actuating the counting and registering mechanism by the vertical reciprocatory movement of the lever.
- 25 3. In combination with a downwardly discharging faucet body having a counting and registering casing above the same, counting and registering mechanism in the forward portion of said casing, a lever pivoted above the faucet body in the rear end of the counting and registering casing, said counting and registering casing having an opening immediately above the discharge opening of the faucet, and said lever extending above the edges of said opening and adapted to be depressed to the level of said edges by the weight of a vessel of which the bail is deposited upon the portion of the lever extending above said edges, a spring for raising said lever when the bail is removed, and means carried by the front end of said lever for actuating the counting and registering mechanism by the vertical reciprocatory movement of the lever.
- 30 4. In combination with a downwardly discharging faucet body having a counting and registering casing above the same, counting and registering mechanism in the forward portion of said casing, a lever pivoted above the faucet body in the rear end of the counting and registering casing, said counting and registering casing having an opening immediately above the discharge opening of the faucet, and said lever extending above the edges of said opening and adapted to be depressed to the level of said edges by the weight of a vessel of which the bail is deposited upon the portion of the lever extending above said edges, a spring for raising said lever when the bail is removed, and means carried by the front end of said lever for actuating the counting and registering mechanism by the vertical reciprocatory movement of the lever.
- 35 5. In combination with a downwardly discharging faucet body having a counting and registering casing above the same, counting and registering mechanism in the forward portion of said casing, a lever pivoted above the faucet body in the rear end of the counting and registering casing, said counting and registering casing having an opening immediately above the discharge opening of the faucet, and said lever extending above the edges of said opening and adapted to be depressed to the level of said edges by the weight of a vessel of which the bail is deposited upon the portion of the lever extending above said edges, a spring for raising said lever when the bail is removed, and means carried by the front end of said lever for actuating the counting and registering mechanism by the vertical reciprocatory movement of the lever.

registering casing above the same, counting and registering mechanism in the forward portion of said casing, a lever pivoted above the faucet body in the rear end of the counting and registering casing, said counting and registering casing having an opening immediately above the discharge opening of the faucet, and said lever extending above the edges of said opening and adapted to be depressed to the level of said edges by the weight of a vessel of which the bail is deposited upon the portion of the lever extending above said edges, a spring for raising said lever when the bail is removed, and means carried by the front end of said lever for actuating the counting and registering mechanism by the vertical reciprocatory movement of the lever, a device for preventing the depression of said lever, and means actuated by the opening of the faucet valve for withdrawing said preventive device from said operative position.

60 6. In combination with a faucet, counting and registering mechanism, and means for operating said mechanism, arranged to be actuated by the suspension from the faucet of a sufficiently weighted receptacle, the faucet valve having a groove, a device for preventing the actuation of said means, and having a part adapted to enter said groove, a spring for moving said part into said groove, said means being shaped to abut against said device when said part is in the groove and to escape said device when the part is outside of the groove.

ALBERT J. GRANBERG.
